UNITED STATES PATENT OFFICE.

FRANK E. KINSMAN, OF PLAINFIELD, NEW JERSEY.

ELECTRIC-LIGHTING SYSTEM.

SPECIFICATION forming part of Letters Patent No. 407,895, dated July 30, 1889.

Application filed October 13, 1887. Serial No. 252,220. (No model.)

To all whom it may concern:

Be it known that I, FRANK E. KINSMAN, of Plainfield, in the county of Union and State of New Jersey, have invented an Improvement in Electric Lighting, of which the following is a specification.

Heretofore an electric current of high potential has been transmitted through a main conductor and through the primary of a converter at a distance so that the current set up in the secondary of the converter is of lower potential and of greater quantity for actuating electric lights in the secondary circuit. Reference is hereby made to Letters Patent No. 351,589 for a description of a converter of this character. The secondary current set up, as aforesaid, is alternating and adapted to incandescent electric lights; but before my invention an arc-light had not been successfully introduced into the secondary circuit containing or adapted to contain incandescent lights. If a secondary alternating current, as aforesaid, is passed through the controlling-magnets in an arc light, the alternations of the current will render unreliable or impracticable the magnetic regulating mechanism for drawing the arc between the carbons and maintaining the proper length of arc, because the magnet becomes highly heated and injured or destroyed by the Foucault currents.

By my present improvements I am enabled to employ upper and lower carbons of the same length in an arc lamp, and to regulate the feed of the carbons and the length of the arc by the action of a magnet or magnets in the most perfect and reliable manner, and to introduce one or more arc lights in multiple arc between the main conductors in the secondary or induced circuit.

In carrying out my invention I have made use of an electric lamp corresponding generally to that set forth in Letters Patent No. 330,351, granted November 10, 1885, to Otto Romanze; but my invention is not limited to such a lamp, and I have modified the same in the particulars hereinafter named, whereby injurious effects from an alternating current are avoided.

In the drawings, Figure 1 is a diagram illustrating the connections between the lamp and

the primary and secondary circuits. Fig. 2 is an elevation, in larger size, of the lamp; and Fig. 3 is a separate elevation, and Fig. 4 a plan, of the core. Fig. 5 is an elevation, and Fig. 55 6 a plan, of the core made of strips of iron.

The core A, through which the upper-carbon holder B usually passes, is suspended by the adjustable spring C, and the carbon-holder B has upon it a rack, the teeth of which engage a pinion D, and upon the shaft of this pinion is a wheel E and pulsator F, that regulate the downward feed of the carbon-holder, and there is a detent a, that stops the pulsator when the core A is drawn up into the helix G by the increase of current through the helix and the electric circuit, of which such helix forms a part. The feed mechanism and the construction of the carbon-holders may, however, be varied.

I have discovered that when the core A is divided up longitudinally and when such core projects below the helix a sufficient distance the helix and core can be made use of in regulating the arc of the lamp when alternating secondary currents pass through the said helix. The soft-iron core is slotted longitudinally either entirely through the core or else the slots do not all extend through the lower end of the core, so as to leave the necessary connections between the parts of the core; but I prefer to employ longitudinal strips of soft iron around a brass, vulcanite, or other non-magnetic tube, and to bind these wires or strips to the tube by a layer of paper or other material wrapped around the said longitudinal strips, so as to form a tubular core that will not become heated by the Foucault currents. The core is to be placed and adjusted so that it will not pass through the helix, but will project at the end thereof sufficiently for the varying magnetic attraction due to the greater or less length of the arc between the carbons to adjust the carbon-holder and draw the arc or feed the carbon.

Referring to the diagram, Fig. 1, the primary circuit M M' leads to any suitable dynamo or other source of electric energy of high potential; and N illustrates the primary of the inductorium or converter, and O the secondary of said converter, the latter being of larger wire than the wire of the primary,

so that the current will be of greater quantity but lower potential than the primary currents.

The wires M^2 M^3 from the secondary of the converter are to receive between them incandescent lights in multiple arc, as illustrated at P, and the arc lamps constructed as aforesaid are also introduced between M^2 M^3 in multiple arc either singly, as at Q, or with two or more in multiple-arc series, as at Q^2 Q^3 , according to the size of the arc lamp and the current to which it is adapted; and it will be found that when the arc lamp is constructed as hereinbefore indicated such lamp can be used in multiple arc or multiple-arc series in the secondary circuit of a converter, and that incandescent lamps can also be used in the same circuit without injuriously affecting either the arc lamp or the incandescent lamps.

There should be a switch s to each lamp. Where the lamps are used in multiple arc the same should break the multiple-arc circuit when the lamp is extinguished, and when the lamps are used in series such switch should be a circuit-preserving switch of any known character, so as not to break the main-line circuit when one lamp is extinguished.

It is well known that a secondary current of low potential is not dangerous to persons handling arc lamps; hence the risk of danger is reduced to a minimum.

The magnetic energy developed in a solenoid is augmented by the use of a slotted core; hence heavier carbons can be used in my improved lamp without any stronger current being required.

The ends of the two carbons will be similar in shape as they are burned, because the cur-

rents are alternating, and if there is not sufficient light below the lamp a reflector around the upper part can be made use of.

I claim as my invention—

1. The combination, with the primary and secondary circuits and the converter therewith connected, having a small wire in the primary and a large wire in the secondary, of an arc lamp having a carbon-holder, a helix in the secondary circuit, and a tubular core divided longitudinally and projecting below the helix, and mechanism for connecting the carbon-holder and core for regulating the carbon-holders, substantially as set forth.

2. The combination, with the primary and secondary circuits and a converter in such circuits, of an electric-arc lamp and regulating mechanism having an electro-magnet the helix of which is in the secondary circuit, and a tubular core for the same through which the carbon-holder passes, substantially as specified.

3. The combination, with the primary and secondary circuits and the converter therewith connected, having a small wire in the primary and a large wire in the secondary, of incandescent and arc lamps in the secondary circuit and a helix also in the secondary circuit, and a core and mechanism acted upon by the same for moving and regulating the carbon-holder of the arc lamp, substantially as specified.

Signed by me this 10th day of October, A. D. 1887.

FRANK E. KINSMAN.
